United States Patent Office

Des. 194,443
Patented Jan. 22, 1963

194,443

SLIDE PROJECTOR OR SIMILAR ARTICLE

Robert Boggild and William L. Dale, both of
5463 Hill and Dale Drive, Cincinnati, Ohio

Filed June 21, 1961, Ser. No. 65,663

Term of patent 14 years

(Cl. D61—1)

—FIG. 1

—FIG. 2

FIGURE 1 is a perspective view of a slide projector or similar article embodying the new design;

FIGURE 2 is a rear elevational view thereof.

The side not shown is substantially a mirror image of the side shown.

We claim:

The ornamental design of a slide projector or similar article, as shown and described.
